[57] CLAIM

The ornamental design for a wall-mounted hanger strip, as shown and described.

DESCRIPTION

FIG. 1 is a front elevational view of a wall-mounted hanger strip showing my new design;

FIG. 2 is a right side elevational view thereof, the left side being a mirror image thereof;

FIG. 3 is a rear elevational view thereof;

FIG. 4 is a top plan view thereof;

FIG. 5 is a bottom plan view thereof;

FIG. 6 is an enlarged vertical cross-sectional view thereof, taken along line 6—6 of FIG. 1; and,

FIG. 7 is a top, front, and right side perspective view thereof.

FIG.1

FIG.2
